CLAIM

The ornamental design for the mobile phone, as shown and described.

DESCRIPTION

FIG. 1 is a perspective view of the mobile phone showing our design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view thereof with strap attachment. The broken line showing of a strap in FIG. 8 is included for illustrative purposes only and forms no part of the claimed design.

1 Claim, 4 Drawing Sheets
